(57) **CLAIM**

The ornamental design for a hose with flexible sleeve, as shown and described.

DESCRIPTION

FIG. 1 is a right side view thereof;

FIG. 2 is a left side view thereof; and,

FIG. 3 is a front view thereof.

The broken lines in the drawings illustrate portions of the hose with flexible sleeve, and form no part of the claimed design.

The hose is shown with a symbolic break in its length. The appearance of any portion of the hose with flexible sleeve beyond the break line forms no part of the claimed design.
